United States Patent

Des. 238,931

Patented Feb. 24, 1976

238,931

HAND CARRIED DISPLAY PACKAGE

Henry J. Du Molin, Rte. 1, Highway 23,
Port Sulphur, La. 70083

Continuation-in-part of design application Ser. No.
247,907, Apr. 26, 1972. This application Sept. 13,
1973, Ser. No. 396,910

Term of patent 14 years

Int. Cl. D9—99
U.S. Cl. D9—184

FIG. 1

FIG. 2

FIG. 3

FIG. 1 is a perspective view of a hand carried display package showing my new design with a portion of the net broken away for convenience of illustration,

FIG. 2 is a top plan view thereof on a reduced scale, and

FIG. 3 is an elevational view thereof on a reduced scale.

This is a continuation-in-part of design application Ser. No. 247,907 filed Apr. 26, 1972.

I claim:

The ornamental design for a hand carried display package, as shown and described.
